[57] CLAIM

The ornamental design for a linear embossed spine panel and cover for ring binder, as shown and described.

DESCRIPTION

FIG. 1 is a front perspective view from the right side of my linear embossed spine panel and cover for ring binder; FIG. 2 is a front elevational view thereof;

FIG. 3 is a top view thereof, with the bottom view being the mirror image thereof;

FIG. 4 is a right side elevational view thereof;

FIG. 5 is a cross-sectional view taken along line 5—5 of FIG. 2; and,

FIG. 6 is a cross-sectional view taken along line 6—6 of FIG. 4.

The remainder of the ring binder notebook structure depicted by means of broken lines in FIGS. 1 and 3 has been shown for illustrative purposes only and forms no part of the claimed design.
